UNITED STATES PATENT OFFICE.

ELIHU THOMSON, OF NEW BRITAIN, ASSIGNOR TO THE THOMSON-HOUSTON ELECTRIC COMPANY, OF CONNECTICUT.

SAFETY DEVICE FOR ELECTRIC-ARC LAMPS.

SPECIFICATION forming part of Letters Patent No. 289,580, dated December 4, 1883.

Application filed March 8, 1883. (No model.)

To all whom it may concern:

Be it known that I, ELIHU THOMSON, a citizen of the United States, and a resident of New Britain, in the county of Hartford and State of Connecticut, have invented certain new and useful Improvements in Safety Devices for Electric-Arc Lamps, of which the following is a specification.

My invention relates to electric-arc lamps, and is designed to prevent permanent rupture of the general circuit upon which a series of lamps are burning in case any one of said lamps should fail to feed properly.

My invention provides a novel means for bringing the carbons together and holding them in contact in case the lamp burns with an abnormally long arc, or in case the arc is extinguished from any cause.

My invention consists, first, in making the guides for the carbon-rod movable and providing a means whereby said guides may be allowed to drop by their own weight, or may be drawn positively downward, as by a spring, in case of an abnormally long arc.

My invention consists, secondly, in forcing the regulating armature-lever, or the parts supporting the feed mechanism, to recede by some positively-acting mechanism normally held out of action, but brought into action by an abnormal increase in the length of arc, so as to not only produce a complete release of the carbon-rod, but also to prevent re-engagement of the regulating mechanism.

My invention consists, thirdly, in providing a means whereby all the parts of the lamp that are in contact with the carbon-rod may be allowed to drop or recede upon an abnormal increase in the length of arc, so as to insure a complete movement of the carbon-rod and a contact of the two carbons in case, through a defect of any portion of the feed mechanism, a sticking of the carbon-rod, or other defect, the carbon-rod should fail to feed properly. This portion of my invention is ordinarily accomplished by combining the two first features of my invention, since the feed mechanism and the guides are ordinarily the only parts which, under any circumstances, could restrain the movement of the carbon-

rod. I ordinarily prefer to carry out my invention by connecting to the movable guides a rather stiff spring or springs, which tend to pull them downward or in a direction toward the arc, and in restraining said spring from action by a detent which engages with the guides or other parts connected with them, and is released by any suitable device or devices whenever the arc becomes abnormally lengthened. The guides and their connected parts might, however, be made sufficiently heavy to act positively on the removal of the restraining catch or detent. For controlling or releasing the detent, I ordinarily prefer to use a supplemental electro-magnet or armature suitably arranged or connected to cause a release of the detent upon an abnormal increase in the length of arc; but I do not limit myself in this respect, as the gist of my invention consists in making the guides movable, and in releasing them automatically by any suitable means brought into action by an abnormal increase in the length of arc. It would therefore be within my invention to employ other electro-responsive devices instead of electro-magnets, or to release the detent by the mechanical action of any portion of the regulator-lever or mechanism when allowed to recede sufficiently far by an abnormal increase in the arc length.

In carrying out the third feature of my invention it is sufficient to produce a complete and continued release of the feed mechanism by any means, and I may therefore, in this combination, employ a mechanism like a spring, which is normally restrained or held out of action by a detent or catch until the proper time; or I may arrange for cutting out the lifting electro-magnet at the same time that the guides are released.

In the accompanying drawings, Figure 1 is an elevation of an electric lamp embodying one form of my invention, and showing the invention applied to a clutch or clamp lamp having one of the well-known magnet systems employed for giving the requisite movement to the carbon adjusting or feeding mechanism. In this form of my invention the catch which prevents the carbon-guides from moving, is

controlled or released by the action of an electro-magnet, which I shall term a "safety-magnet," and which magnet is here energized at the proper time by the closing of a contact 5 connected to the lever of the regulating mechanism. Fig. 2 shows the safety devices of Fig. 1 separated from the other parts, and in the position occupied by them while the lamp is operating properly. Fig. 3 shows the same 10 devices after they have been released. Fig. 4 shows an equivalent arrangement of circuits and contacts for bringing the safety-magnet into operation. Figs. 5, 6, and 7 show an improved device for conveying the current to the 15 carbon rod or carrier. Figs. 8, 9, 10, 11 and 12 show other and modified arrangements of my invention.

In Fig. 1, D is a lifting or main-circuit magnet placed in the usual connection, embracing 20 the carbons and the arc at E E'. Its circuit is indicated by the numeral 5, and passes from the main wire at 2 through the coils of D to the guide-tube T, to the carbon-rod R, through the arc at E E', and out at 3. S is the usual 25 derived-circuit magnet, of high resistance, placed in the connection 6 around the arc. C is a carbon-holding clamp or feed-controlling device, of any suitable construction—such, for instance, as is shown in my prior patent, 30 No. 272,353, Figs. 2 and 3—and R is the supporting-rod or carrier for the carbon E. L is the lifting frame or lever actuated to raise and lower the clamp by the direct and derived 35 circuit magnets D S, in the usual way. T is a frame or sleeve which carries the usual guides for the carbon-rod R, said guides being formed at the upper and lower ends of said sleeve or frame, as shown in Figs. 2 and 3. The frame or sleeve, and therefore the guides, 40 is movable, and is itself guided in fixed openings in the general frame of the lamp H and in a supporting arm, H', for the magnet D and a portion of the clamp devices C. The frame T and the guides for the carbon are 45 free to move vertically, either by their own weight or by the action of a spring; but are normally restrained from movement by means of a catch or detent A, which engages with a projection, B, on frame T, but may withdraw 50 from engagement with said projection by the action of the safety-magnet M, with the armature or equivalent portion of which said catch or detent is suitably connected. When the frame or guides are released, a spring, F, 55 or a weight pulls them down forcibly in any suitable way—as, for instance, through the intervention of a piece, P, provided with a projection, as shown, for engagement with the frame T. The spring F also acts, through piece P and 60 a projection, a, to pull the lever L down forcibly and to hold it down, thus producing a complete disengagement of the carbon-feeding devices, and also lowering the same, so that in case any portion of said devices should stick 65 to or tend to hold the carbon-rod said rod will nevertheless be lowered. The spring F

is sufficiently strong to also prevent re-engagement of the lifting or feeding devices under the action of the regulating-magnet system. The magnet M is energized by the closing of 70 contacts K, suitably connected with the feed-regulating lever L, or equivalent portion of the feed-regulating mechanism, and suitably adjusted or placed to close a circuit, 9, containing the magnet M and derived from the 75 main circuit, whenever an abnormal or dangerous increase in the length of arc occurs and allows said lever to recede to an abnormal extent. When an abnormal arc and failure to feed occurs, the contacts at K being closed, 80 the magnet M is energized, so that the frame T and guides for the carbon are pulled down, as also the lever L, and the upper carbon, owing to the release and lowering of all the parts that could tend to hold it up, is lowered into 85 contact with the lower carbon, where it remains until the lamp is repaired or readjusted.

In Fig. 2 the parts are shown enlarged and in section in their normal or sustained position. The frame or tube T may be replaced 90 by any mechanical equivalent, forming the sole guide for the carbon-rod R. At T' is shown a convenient contact for maintaining good electrical connection with the rod R through the sleeve T, but is unessential to its 95 working. The same letters are used as in Fig. 1.

In Fig. 3 the detent or catch A is shown withdrawn by the magnet M, and the parts have descended under the influence of their 100 weight, but assisted by the force of the spring F, which, though desirable, is not essential if the parts are made of considerable weight. It is obvious that the lug a might be connected to the tube or frame T instead of to the piece 105 P. This arrangement is shown in Fig. 12, and would be a preferred arrangement if the spring were dispensed with and the weight of the parts depended upon.

In Fig. 4 is shown another arrangement of 110 circuits, whereby the magnet M may be energized at the proper time. The magnet M is placed in a direct circuit, and is normally shunted by contacts at K' until such contacts are opened by the lever L under the increased 115 attraction of the derived-circuit magnet when the arc is abnormally lengthened. This arrangement is an obvious equivalent of that already described. The contact-spring T' is shown in Figs. 5, 6, 7 as consisting of a comb, 120 W, of spring metal, Fig. 7, bent so as to lie around the carbon-rod, and each tooth formed in the arc of a circle. The comb thus bent is seated in a cavity or support at the lower end of T. This I find to be a very cheap contact 125 device, even for use in a fixed position in a lamp to make connection with a carbon-rod. The comb W is of thin hard-rolled copper, preferably.

In Fig. 8 a safety-magnet, M, is arranged to 130 be normally in circuit, but to be cut out by contacts K" upon the abnormal increase of a

derived-circuit magnet, S', (with the armature-lever of which contacts K" are connected,) forming, it may be, a portion of the ordinary regulating derived circuit in which the regulating derived-circuit magnet S is placed. In this case the magnet M, by its attraction, holds the catch A in engagement under normal working, and it is withdrawn by a spring, Z, on the cessation or decrease of magnetism in M, produced by the closing of the contacts at K" when the arc increases abnormally, the retract- or 17 being suitably adjusted for that purpose. The spring Z may be dispensed with if a proper inclination is given to the detent-surfaces to enable B to slide by or past A under its normal tendency to descend. The objection to the arrangement Fig. 8 is the necessity of providing for the maintenance of engagement of A and B until the current is put on, or manual operation or setting of the parts when the lamp is started. In Fig. 9 the sleeve T is replaced by simple ring-guides T² T² for the rod R, said rings being united by a frame or rod held vertical by portions of the lamp-case, as H, but free to move when the catch A may be released by a magnet acting on it directly; or it may be released by the spring Z upon the removal or release of a second detent, G, under the control of a derived-circuit magnet, S', or under the control of a magnet, M, thrown into action by the derived-circuit magnet, as in former figures. For the purpose of depressing the regulating-lever simultaneously with the lowering of the guides, an electrical arrangement such as is shown in Fig. 9, whereby the lifting-magnet D is short-circuited or cut out simultaneously with the lowering of the frame and guides T, may be employed. When thus short-circuited, the magnet 40 loses its lifting-power and does not regain it until the parts are restored to their normal position, so that the lever L will be depressed by its own weight, combined with the action of the derived-circuit regulating-coil, and will retain its position after the carbons come together. The demagnetization of the main-circuit coil is here shown as effected by a short-circuiting of the same through contacts m n, one of which, m, is connected to T, and subserves the same function as the mechanically-acting projection a, Fig. 12, and Figs. 1, 2, and 3. Other means might be employed for removing the current from the main-circuit magnet D at the same time that the arc abnormally lengthens and the guides are lowered, and other mechanisms might be employed in this connection for lowering the clutch or regulating mechanism, provided they be properly constructed and arranged to come into operation upon an abnormal increase in the length of arc, and to act simultaneously with the lowering of the guides or other parts bearing upon or connected to the carbon-rod.

In Fig. 10 each bushing or guide for the carbon-rod R is provided with a separate catch, A, and is mounted so as to be movable in the

lamp frame or case H H, and acted on by its depressing-spring. The magnet M, when actuated, causes the release of both bushings T² T², either simultaneously or successively, as 70 may be desired, according to the set of the catches A. The upper bushing, T², may have a flange, r, which, when it is released, holds the regulating-lever L down.

Fig. 11 shows an arrangement whereby the supplemental safety-magnet might be dispensed with and the mechanical action of the regulating-lever L or other portion of the regulating mechanism employed for releasing the catch and guides whenever such mechanism recedes abnormally under the influence of an abnormal flow of current in the derived-circuit coil. G is the extra detent-lever, which holds the catch A in engagement with B, and is arranged in the path of a projection, 15, 85 from the lever L, so that when the lever is drawn down abnormally under the action of the derived-circuit regulating-coil the catch A will be removed.

Many other devices for dropping the guides 90 at the proper time will readily suggest themselves to those skilled in the art, and I do not therefore limit myself in this respect, the gist of my invention consisting in making the guides for the carbon-rod movable and releasing said guides upon a failure of the carbon to feed properly, so as to insure a complete release of said carbon and a contact of the same with its opposite carbon. Nor do I limit myself as to the means for insuring a release 95 and drop of the carbon-feeding mechanism simultaneously with the lowering or release of the guides, since the essence of my invention, so far as the third head thereof is concerned, consists, broadly, in automatically releasing or 100 freeing all the portions of the lamp connected to or in contact with the rod upon an increase in the length of arc due to a failure of the carbon to feed properly.

The details of mounting the guides so that 110 they move at the proper time and the form of the detent or catch which holds them up may be varied indefinitely.

The safety-magnet which controls or releases the catch may be energized in any way, provided it be properly connected and arranged to release the catch at the proper time, as stated.

My invention may obviously be applied to any form of electric-arc lamp.

What I claim as my invention is—

1. In an electric lamp the guides for the carbon-carrier of which are made movable, the combination, with said guides, of detaining mechanism holding said guides stationary during normal feeding of the carbon, and means for releasing said guides upon failure of the carbon to feed properly.

2. The combination, with a carbon-carrier, of movable guides normally held stationary during the feed of the carrier, means for releasing said guides when an abnormal increase

in the length of arc occurs, and for simultaneously lowering with a positive movement the portion of the regulating mechanism which supports the feed-clutch or equivalent feed mechanism.

3. The combination, with the upper or movable carbon-carrier in an electric lamp, of means for normally detaining or supporting those portions of the lamp outside of the feed to devices that are in contact with said carbon-carrier, and mechanism for releasing or withdrawing said supporting or detaining devices upon failure of the carbon-carrier to feed properly.

15 4. In an electric lamp, the combination, with the movable and supporting portion for the feed-regulating mechanism, of a supplemental retractor normally held out of action upon said lever during feed of the carbon, and means 20 for releasing said retractor upon failure of the carbon to feed properly.

5. The combination, with the carbon-carrier in an electric-arc lamp, of guides and feed-regulating devices for said carrier, made movable, a detent or catch for normally holding 25 the guides from movement, means adapted to act upon and lower the feed-regulating devices, also normally held out of action by a catch or detent, a releasing or safety electro-magnet for releasing said catches, and means 30 for rendering said magnet operative upon an abnormal increase in the length of arc.

6. The combination, with the lever L, which supports or actuates the feed-regulating mechanism, of a supplemental spring normally held 35 out of action by a catch or detent, and means for releasing said catch or detent upon an abnormal increase in the length of arc.

7. The combination, with the lever which 40 supports or actuates the feed-regulating mechanism, of a supplemental spring normally held out of engagement with the said lever by a catch or detent, a releasing or controlling electro-magnet for said catch, and means for bringing 45 said magnet into or out of action upon failure of the carbon to feed properly.

8. The combination, in an electric-arc lamp, of a frame supporting movable guides for the carbon-carrier, a spring for acting on said

frame so as to pull it downward or toward the arc, a catch normally engaging with the frame, and means for releasing the catch upon an abnormal increase in the length of arc.

9. The combination, in an electric-arc lamp the guides for the carbon-carrier of which are 55 made movable, of a spring for acting on said guides so as to pull them toward the arc, a catch or detent normally holding said guides from movement, and a controlling electromagnet for said catch, which releases said 60 guides upon an abnormal increase in the length of arc.

10. The combination, with the guides, of the frame T, carrying the same, a spring, F, an engaging-plate, P, for engaging with the frame 65 and with the lever L, and a detent for holding the frame and the spring out of action.

11. The combination, with the frame T, of a detent normally holding the same from movement, a spring which tends to pull the frame 70 downward, and a lug or projection operated by the spring for engaging with the lever of the regulating mechanism when the frame is released.

12. The combination of frame T, carrying 75 the guides for the carbon-carrier, a catch, A, and a lug or projection, a, moving simultaneously with the frame for producing a receding movement of the regulator-lever L simultaneously with the release and movement of 80 the guides.

13. The combination, with the carbon-carrier, of a contact-spring formed from a comb, W, the continuous band of which is bent in a circle around the carrier, while its teeth entirely surround said carrier and are bent on a line parallel with the carrier, substantially as 85 shown and described, so that the curved portion of the teeth rest against the surface of the same.

Signed at Boston, in the county of Suffolk and State of Massachusetts, this 6th day of March, A. D. 1883.

ELIHU THOMSON.
